UNITED STATES PATENT OFFICE.

ELROY A. CHASE, OF NORTHFIELD, VERMONT.

GRINDING WHEEL.

Application filed July 2, 1923. Serial No. 648,870.

This invention relates to a wheel for grinding granite and other similar material. While capable of general application, this new wheel is particularly adapted for grinding bevelled faces or "washes" on the edges of blocks of stone used for monument bases or other similar purposes. This grinding operation is commonly performed with the use of small steel shot as the grinding or crushing agent, although certain coarse abrasive substances may also be used with some degree of success.

One object of my invention relates to the provision of a grinding wheel for such purposes, rigidly attached to its driving shaft so that it may be caused to operate at a definite and predetermined angle.

Another object is to provide a center feed for a wheel thus rigidly supported, with novel features of adaptation by which a feed near the axis of the wheel is accomplished without the use of a hollow shaft.

A third feature of my invention relates to improved details of construction by which a wheel may be very easily built up from relatively simple detail parts and in which repairs may be very easily accomplished.

My invention further relates to arrangements and combinations of parts which will be hereinafter described and more particularly pointed out in the appended claims.

A preferred form of the invention is shown in the drawings in which

Fig. 1 is a plan view of my improved wheel;

Fig. 2 is a sectional elevation thereof affixed to a driving shaft;

Fig. 3 is a perspective view of the wheel head or top plate;

Fig. 4 is a perspective view of one of the grinding or ironing rings; and

Fig. 5 is a perspective view of a portion of a straight rectangularly grooved bar from which a grinding ring may be conveniently formed.

Referring to the drawings, I have shown a grinding wheel of simple construction comprising a head or top plate 10 having a hub portion 11, a ring holding plate 12 detachably secured to the plate 10 by bolts 13, and a plurality of grinding or ironing rings 14 secured to the plate 12 by bolts or screws 15.

For general purposes, it is found desirable to make the rings 14 of wrought iron or soft

steel and I have illustrated in Figs. 4 and 5 a convenient method of forming these rings. As suggested in these figures, a straight rectangular bar 16 is first provided with V-shaped grooves or notches 17 extending diagonally across the bar and distributed throughout its length. After the bar 16 is thus grooved or notched, it is cut to the required length and the bar is then bent to the circular form shown in Fig. 4. It is also provided with tapped holes 18 by which it may be secured to the lower face of the ring holding plate 12.

A series of bars of different lengths are naturally required to make each set of concentric rings for a grinding wheel. Whenever the rings become too badly worn, they are easily removed and replaced without any necessity for providing new plates 12 or heads 10.

For the purpose of feeding the steel shot or other abrasive to the work at the center of the grinding rings, I provide a series of helical feeding passages 20 in the hub portion 11 of the head or top plate 10. These feeding passages 20 are substantially similar to a plurality of multiple internal screw threads, square in cross section and disposed in a downwardly converging relation as clearly indicated in Fig. 2. The ribs or ridges separating adjacent spaces or passages are machined at their inner edges and form a conical seat for the tapered lower end of a drive shaft 22 by which the wheel is supported in suitable bearings 23.

Near its lower face, the head 10 is provided with a recess 24 to receive a washer 25 and binding screw or bolt 26 by which the wheel head is firmly secured upon the tapered end of the shaft 22. The washer 25 is recessed or cut away at suitable portions of its outer edge so that it does not obstruct the lower ends of the passages 20.

At their upper ends, the ribs between the passages 20 are narrowed down to thin edges 28, as shown in Fig. 3, so that shot or abrasive may be easily fed thereto and will not be widely scattered by contact with a rapidly revolving wheel surface.

A steel ring 30 (Fig. 2) is preferably secured around the upper end of the hub 11, giving increased strength to that portion of the hub where the least stock remains after the formation of the passages 20. It will be noted that the passages 20 converge down-

ward and deliver the grinding material through a center opening 31 in the ring holding plate 12.

Having described the details of construction of my improved grinding wheel, the advantages thereof will be readily understood. The wheel is rigidly seated on the shaft 22 so that it may be used to grind a bevel or wash at any desired angle and this angle will be maintained by the wheel in a manner quite impossible with the old and common loose or universal connection between the wheel and the driving shaft. Furthermore, with this construction I am able to secure all of the advantages of a center feed while at the same time I avoid the necessity for using a hollow shaft feed, which is at all times objectionable and particularly so in connection with grinding or ironing operations where the grinding material, if raised above the shaft bearings, sooner or later works into the bearings with destructive effect.

Having thus described my invention and the advantages thereof, I do not wish to be limited to the details herein disclosed otherwise than as set forth in the claims, but what I claim is:—

1. In a grinding machine, a shaft, a wheel head rigidly secured thereto, and a plurality of concentric grinding rings secured to said head and provided with upwardly and rearwardly inclined pockets across the inner faces of said rings.
2. A grinding wheel having a plurality of separately formed, concentric grinding rings detachably secured to its lower face and each ring having a series of V-shaped upwardly and rearwardly inclined grooves formed across its inner face.
3. A grinding wheel having a hub portion formed with an opening therethrough designed to receive a shaft, and having a plurality of helical, downwardly-converging feed passages communicating with said

opening therein effective to deliver grinding material at the axis of said wheel.

4. In a grinding machine, a shaft having a tapered end portion and a grinding wheel rigidly seated thereon, the hub portion of said wheel having a plurality of helical feeding passages, the inner faces of which are closed by said shaft and said passages being inwardly and downwardly directed toward the center of said wheel.

5. A grinding machine comprising a shaft and a grinding wheel rigidly attached thereto, the shaft engaging portion of said wheel having feeding passages formed therein adjacent said shaft; grinding rings mounted on the lower face of said wheel each provided with upwardly and rearwardly inclined pockets on the inner face thereof, and said feeding passages being in communication with said rings.

6. A grinding machine comprising a shaft and a grinding wheel rigidly attached thereto, the shaft engaging portion of said wheel having a plurality of helical feeding passages formed therein open at their inner sides and said passages being separated by ribs in said portion providing a tapered seat for said shaft; grinding rings mounted on the lower face of said wheel, each provided with upwardly and rearwardly inclined pockets on the inner face thereof, and said feeding passages being in communication with said rings.

7. In a grinding machine, a shaft having a tapered end portion, a grinding wheel having a hub, said hub having a plurality of helical feeding passages formed therein open at their inner sides, said passages being separated by ribs in said hub providing a tapered seat for said shaft, said ribs being narrowed down to thin edges at their upper ends.

In testimony whereof I have hereunto affixed my signature.

ELROY A. CHASE.
